BY

Gottlieb P. Polachek
ATTORNEY.

UNITED STATES PATENT OFFICE.

FRANK HAZNER AND LEOPOLD GASIOREK, OF NEWARK, NEW JERSEY.

RAIL-FASTENER.

1,387,052.

Specification of Letters Patent.

Patented Aug. 9, 1921.

Application filed May 4, 1921. Serial No. 466,855.

To all whom it may concern:

Be it known that we, FRANK HAZNER and LEOPOLD GASIOREK, citizens of Poland and the United States, respectively, residing at 5 Newark, in the county of Essex and State of New Jersey, have invented certain new and useful Improvements in Rail-Fasteners, of which the following is a specification.

This invention relates to track rail fastening means, for securing the rails to the ties and for securing the rail ends to one another.

The invention has for an object to provide a simple and efficient device of this kind 15 which will securely hold the rails, and properly buttress and reinforce the same at the joints.

For further comprehension of the invention, and of the objects and advantages 20 thereof, reference will be had to the following description and accompanying drawings, and to the appended claim in which the various novel features of the invention are more particularly set forth.

Figure 1 of the drawings is a plan view 25 of a section of a railroad track having the rails secured to the ties by our improved fastening means.

Fig. 2 is a detail perspective view showing 30 the arrangement at the rail joints.

Fig. 3 is an enlarged side elevation at a rail joint, parts being broken out into longitudinal section.

Fig. 4 is a transverse section on the line 35 4—4 of Fig. 3, but on a smaller scale.

Referring now to the drawings, the reference numerals 10 and 11 indicate adjacent rails, the usual ties or sleepers being shown at 12. As here embodied our improved rail 40 fastening means comprises a chair-plate 15 which rests upon the tie 12 and has the rail resting in turn thereon, this plate having at one side an integral projection 16 which projects over one side of the base flange of 45 the rail and has a fish-plate element 17 formed on its upper end which fits snugly between the base flange and tread of the rail, this fish-plate element 17 being extended at opposite ends beyond the chair-plate 15.

Upon the opposite side of the rail the chair-plate 15 is formed with a pair of grooves 50 18 on its upper face, these grooves extending longitudinally of the rail from edge to edge of the plate and being inclined downwardly and away from the rail as shown.

Upon the grooved portion of the plate 15

is seated an angular bracket 20 of a shape complementary to the projection 16 on the opposite side of the rail and having a fish-plate element 21, similar to the element 17, 60 formed at its upper end and engaging the rail. The bracket 20 has a pair of tongues 23 formed on its under face which are complementary to, and engage slidably in, the grooves 18, the inclined arrangement of the 65 tongues and grooves preventing disengagement thereof by other than a sliding movement of the bracket 20 longitudinally of the rail.

Fixed in the fish-plate element 17 are a 70 pair of projecting studs 25 which are adapted to project freely into registering apertures in the rails to localize the same longitudinally with respect to the fastening means. It will be understood that these studs will only be 75 employed at the rail ends.

To secure the device to the ties 12 spikes 26 are driven through suitable apertures in the inner side thereof and through suitable registering apertures in the brackets 20 and 80 the outer side thereof.

For convenience in properly locating the bracket 20 on the plate 15 we provide the latter with a spring pressed stud 30 adapted to engage in an aperture 31 in the bracket. 85 As shown in Fig. 3 this stud is located in a socket 32 in the plate 15 and the spring 33 surrounds a downwardly extending stem 34 thereof which projects into a recess 35 in the tie and has a collar 36 fixed to its lower 90 end to limit its upward movement.

In the assembly of the device the plates 15 are first placed on the ties and the rails laid thereon, the studs 25 in the fish-plates engaging in the apertures in the rail ends. 95 The brackets 20 are then slid longitudinally into place, the studs 30 being first depressed by hand and springing up into the openings 31. The spikes 26 are then driven into the ties. To dismantle the track the above operation is reversed.

Having thus described our invention what we claim as new and desire to protect by Letters Patent of the United States is as follows:

A rail fastening device comprising a chair-plate having an integral projection on one side adapted to engage over the base flange of the rail, a fish-plate formed on and projecting at its ends beyond said extensions, 110 a bracket adapted to rest on the other side of the chair-plate and engage over the base

flange of the rail, said bracket having longitudinal tongues thereon engaging in complementary grooves in the said chair-plate, a fish-plate element formed on and projecting at its ends beyond said bracket, a tie on which the chair-plate rests, said tie having a recess formed in its upper face, said chair-plate having a socket formed therein in registry with said recess and said bracket 10 having an aperture therein which registers with the said socket, a stud located in said socket adapted to engage in said aperture,

a spring in said socket normally urging said stud upwardly, a stem formed on said stud and extending downward into the recess, and a collar on said stem located in said recess and adapted to bear against the bottom of said chair-plate to limit upward movement of said stud.

In testimony whereof we have affixed our 20 signatures.

FRANK HAZNER.
LEOPOLD GASIOREK.
